UNITED STATES PATENT OFFICE

2,437,874

SHINGLE

James E. Black, Chicago, Ill., assignor to James E. Black, Elam L. Black, Whitfield J. Black, and Virginia Black, a partnership doing business as Black Systems, Chicago, Ill.

Application June 7, 1945, Serial No. 598,131

2 Claims. (Cl. 108—7)

1

This invention relates to shingles used for roofing and the like, and more particularly to those made of flexible roofing material and adapted to interlock with one another.

It is an object of the present invention to provide improved shingles of the interlocking type which have interlocking parts so disposed and related to the main surface covering portions of the shingles that the said surface covering portions conform closely to the surface to which they are attached and the adjacent shingles whether made of normal or heavier weight material, thereby avoiding pockets under the shingles accessible to wind and rain.

The invention has for another object the provision of shingles of irregular contour and including tabs at their outer edges adapted to interlock with adjacent shingles, and in so doing to flex from the plane of the rest of the shingle, said tabs being so disposed on the shingles that they form a regular and pleasing pattern in groups and relative to the exposed edges of the shingles.

As another object this invention comprehends the provision of interlocking parts on the edges of shingles, so disposed and of such a size relative to the shingles that their flexure in locking with other shingles does not cause any undesirable exposure of other surfaces or establish detrimental catches for wind or rain.

A further object of the present invention is to provide an improved shingle of the interlocking type in which irregular contours provide interlocking parts adapted to effective use and service in shingles made of heavy, as well as lighter weights of roofing material.

Other objects and advantages of the invention will be apparent from the following description and the accompanying drawings in which similar characters of reference indicate similar parts throughout the several views.

Referring to the single sheet of drawings:

Figure 1 is a fragmentary plan view illustrating the structure of shingles embodying my invention in a preferred form as well as showing the preferred manner of application of the shingles to a surface;

Fig. 2 is a fragmentary perspective view to an enlarged scale which illustrates the details of the interlocking portions of shingles assembled as shown in Fig. 1; and

Fig. 3 is a fragmentary side sectional view showing interlocked portions of assembled shingles and in which the section is taken substantially on a line 3—3 of Fig. 2 and viewed in the direction indicated by the arrows.

Shingles of the type disclosed are particularly adapted to be cut from sheets of flexible roofing material. They are also adapted to interlock with one another when assembled in the preferred manner as disclosed in Fig. 1 to cover a surface such as a roof.

One consideration in the design of such shingles is that they shall provide a pleasing appearance when assembled. Factors contributing to the pleasing appearance include the symmetry and combination of broken lines and the creation of edge shadow effects unaccompanied by irregular or unsymmetrical folds or warped surfaces.

Considered structurally, shingles of the type disclosed should interlock firmly to hold the covering portions of the shingles in place and without warping the body portion of any shingle so as to effect the creation of an air pocket or a space accessible to driven rain. In some types of shingles it has been the practice to offer the user the choice of either a normal weight shingle material or a material considerably thicker and heavier than the normal weight. The added thickness of the heavier weight material increases the difficulty or makes it practically impossible to lay some types of shingles without having bulges or undesirable warping of the shingle surfaces. As will be more fully explained with reference to the details of structure of the disclosed shingle, it not only provides a well designed and pleasing pattern, but it also is adapted to be easily and effectively laid when made of either the normal or heavier weight material.

Referring to the drawings, shingles 10 are illustrative of a preferred embodiment of my invention and are substantially T-shaped, having head portions 11 and integral shank portions 12. As the shingles are placed upon a surface which is to be covered, the head portions 11 are desirably placed at the top with their substantially straight top edges aligned and extending laterally of the surface so that the substantially parallel sided shank portions 12 extend downwardly. As an aid to proper lateral alignment of the shingles relative to one another, they have at opposite ends of the head portion aligning tabs 13, the outer edges of which are straight and placed in aligned abutment as shown in Fig. 1.

Although there are certain contour irregularities in the edges of the disclosed shingles which result from the desirability of the provision of a shingle shape which permits the cutting of the shingles from a strip of the desired material without appreciable waste, locking tabs 14 and shank tabs 15 have definite functions in the placement

and secure positioning of the shingles. The locking tabs 14 are desirably substantially rectangular and extend downwardly from the head portion 11 along and adjacent opposite sides of the shank portion 12. They are also disjoined from the shank portion 12 by slots 16 so as to be flexible relative to the shank and head portions of the shingle along lines transverse to the longitudinal axis of the shingle. The shank tabs 15 are of substantially the same size as the locking tabs 14 and project laterally in opposite directions from the bottom portions of the side edges of the shank portion 12. It is preferred that the lower edge of each of the shank tabs is aligned with the lower straight edge of the shank portion.

Each shingle including the head portion 11, shank portion 12, aligning tabs 13, locking tabs 14 and shank tabs 15, is symmetrical with regard to a longitudinal center line thereof. In addition to being symmetrical with respect to a longitudinal center line, the respective parts of each shingle are so disposed and of such relative sizes that when two shingles are placed side by side in a common plane with the edges of the aligning tabs 13 abutting, the shank portion 12 of a third shingle fits between the locking tabs 14 of the first-mentioned two adjacent shingles. In such relative positions the shank tabs of the third shingle are slipped under and underlie the locking tabs 14 of the first two shingles while the shank portion 12 and head portion 11 of the third shingle overlie and extend upwardly beyond the upper edges of the first two shingles. The nailing of the shingles to the covered surface is confined to the aligning tabs 13 or the ends of the head portions which are overlapped by the shank portion of a succeeding shingle.

As illustrated in the various views of the drawings, the locking tabs 14 flex outwardly with respect to the head portions 11 when the shank tabs 15 are slipped thereunder. This flexure of the locking tabs is independent of the shank portions of the shingles and along a line transverse to the longitudinal axes of the shingles. In each instance and as particularly well disclosed in Figs. 2 and 3, the shank portion 12 of each shingle is flexed downwardly over the lower edges of the head portions of underlying shingles adjacent the locking tabs 14. This flexure of the adjacent parts of interlocked shingles is substantially opposite but since the flexure of each of the parts is substantially linear and transverse thereto at a position in which those parts are freely flexible, the interlocking positions are assumed without undesirable warping of the shingle body surfaces. That is, the locking tabs 14 flex upwardly along lines at which they are free to flex when the shank tabs are slipped thereunder. Likewise, the shank portions 12, while mainly conforming to the plane surface of the underlying shingles, flex downwardly over the lower edges of the underlying shingles and along lines lateral to the shank portions as well as in substantial alignment with the flexed portions of the locking tabs.

The shank tabs 15 being of substantially the same size as the locking tabs 14, their edges are adjacent in the fully interlocked position and there is no possibility of the shank tabs extending beyond the locking tabs to an extent such that they would underlie and warp an adjacent shank portion of another shingle.

As illustrated in Fig. 3, the body portions of the shingles lie closely together when applied to a surface and conform to the surface to which they are applied. In addition to providing an effective covering for a surface which is well adapted to withstanding wind and weather, the interlocked shingles present a pleasing appearance and pattern as illustrated in the lower right-hand portion of Fig. 1. The exposed shingle edges present an irregular and recurring pattern of broken lines and the separately flexible locking tabs add to that pattern of lines an additional and symmetrical pattern which is somewhat superimposed upon the pattern of lines and is particularly attractive when viewed in three dimensions.

Having thus illustrated and described my invention, what I claim as new and desire to secure by Letters Patent of the United States, is:

1. A shingle of flexible weather resistant material comprising a head portion having parallel lateral edges, three downward projections from the head portion which are severally integral with the head portion but otherwise separate and distinct from each other, two of said three projections being symmetrical locking tabs substantially spaced from each other and equidistantly spaced inwardly from the lateral edges of the head, the other of said three projections being a shank portion substantially wider than and lying between and adjacent to said locking tabs and extending substantially downwardly beyond them, and a pair of locking tab engaging tabs projecting laterally in opposite directions from the lower end of the shank portion, each of said locking tabs being adapted to flex relative to the head portion on a transverse line of flexure without causing wind pocket forming flexure of the proximate lateral edge of the shank portion.
2. A shingle as specified in claim 1 wherein the opposed edges of the shank portion and locking tabs are definitely spaced apart and are parallel with each other and with the lateral edges of the head portion.

50 JAMES E. BLACK.
